CLASP FOR GARMENT SUPPORTERS

John Robie Parker, Toronto, Ontario, Canada,
assignor to Fred Page Higgins, Toronto, Ontario, Canada

Application March 21, 1936, Serial No. 70,032
In Canada August 22, 1936

2 Claims. (Cl. 24—245)

The invention relates to improvements in clasps for garment supporters as described in the present specification and shown in the accompanying drawing that forms a part of the same.

5 The objects of the invention are to provide a simple, inexpensive and efficient clasp particularly adapted for use with hose supporting devices, which will fit snugly against the limb of the wearer and present a smooth exterior whereby to be rendered as inconspicuous as possible, 10 and to provide a clasp which may be easily engaged and disengaged and which will grip the fabric securely without injuring same and which will not slip.

15 With the above and other objects in view the invention consists in the novel features of construction, arrangements and combinations of parts described in the present specification and more particularly pointed out in the claims for novelty following.

20 In the drawing Figure 1 is a plan view of my improved clasp with the clamping parts separated.

Figure 2 is a side view partly in section.

25 Figure 3 is a plan view of the under side of the base plate separate from the stud and its elastic support.

Figure 4 is a plan view of the blank from which the structure shown in Figure 3 is formed up.

30 Figure 5 is a longitudinal sectional view through a modified form of clasp with the clamping parts separated.

Figure 6 is a view similar to Figure 5 but with the parts in operative engagement.

35 Figure 7 is a plan view of the structure shown in Figure 6.

Figure 8 is a plan view of still another modification of the clasp.

Figure 9 is a longitudinal sectional view 40 through the structure shown in Figure 8.

Figure 10 is a view of the under side of the keeper shown in Figure 8.

Like numerals of reference indicate corresponding parts in the various figures.

45 Referring to the drawing 1 is the base plate which may be manufactured of metal, or any other suitable material, and which at one end has a suitable transverse slot 2 therein for the reception of the elastic tape usually employed to suspend the clasp from the garment, the said plate from a point intermediate of its length to the outer, or lower, end thereof being of increased width, as indicated by the numeral 3, and having such margin turned backwardly in spaced parallel 50 relation to the body of the plate to provide an

intermediate opening 4 adapted to slidably receive the neck of the stud 5 whereby the opposed sides of the head 6 of said stud will be slidably confined between the peripheral bottom flange formed by the inturned margin piece 3 and the body of the plate when the clamping parts are in operative engagement.

An elastic 7 secured at its one end to the body of the plate below the slot 2 and extending upwardly over the face of the plate and through an 10 opening 8 in the plate to the under side thereof provides the support for the stud 5. The body of the plate 1 may be cut away as at 9, or may be left intact whereby to provide an unbroken 15 exterior.

In Figure 5 the stud, indicated by the numeral 6a, is adapted to slide wholly within the space between the front wall and the backwardly turned flange and is not provided with a head.

20 In Figures 6 and 7 the base plate, here indicated by the numeral 10, has a longitudinal opening 11 therein for the reception of the head of the stud 12 and this opening reduces towards the lower end of the plate to a size slightly wider than the neck of the stud.

25 The stud 12 extends laterally from a plate 13 which at its end removed from the stud is suspended from an elastic 14 which extends through the base plate 10 to the front thereof and is secured in any desired manner.

30 Secured to the plate 13 above the stud 12 is a resilient boss 14a substantially equal in depth to said stud and of such length that when the stud 12 has reached its lowermost limit in the opening 11 said boss will fill the remaining longitudinal 35 space in said opening. The boss 14a is constructed of soft rubber, or other material having resilient properties, and at its end adjacent to the stud closely follows the contour of the head of said stud whereby the whole device when 40 assembled will present an almost smooth and unbroken outer surface. The boss 14a also serves as a means to hold the plates 10 and 13 against longitudinal displacement in their locked positions over the hose as the plate 10 being positioned below the head of the stud must likewise extend around the top end of the said boss and as the combined longitudinal space taken up by said boss and the neck of the stud is substantially equal to the length of the opening 11 said 45 plates cannot move longitudinally in relation to one another.

50 In Figures 8, 9 and 10 the base plate 15 carries the stud 16 which is preferably substantially triangular in plan with its apex towards the top 55

end of the plate and the keeper 17 is in spaced double wall form with the bottom wall having a convergent slot 18 from the lower end thereof for the reception of the stud. The keeper is suspended from the one end of an elastic element 19 which extends through the base plate near the top end thereof and is secured in any desired manner.

5 The elastic member is of such length that when 10 in its relaxed condition the relation of the opening in the keeper to the stud is such that the said stud will not enter said opening until the elements 15 and 17 have been spread longitudinally 15 against the tension of the elastic the required distance. It will thus be apparent that accidental separation of the plates will be almost impossible of accomplishment due to the fact that to separate said plates they must be moved against the tension of the elastic.

15 It is of course understood that the stud and/or 20 any other part may be constructed of rubber, rubber composition, or any other material which will provide a firm grip but which will not present any sharp or hard surfaces likely to injure the 25 fabric.

The present invention provides an efficient clasp of extremely small depth and attractive in ap-

pearance and while the preferred embodiment and certain modifications have been shown herein and described it is of course to be understood that alterations in details of construction and arrangements of parts as come within the scope 5 of the following claims for novelty may be made.

What I claim is:—

1. A clasp for a garment supporter comprising a slotted upper plate having an elongated stud receiving opening therein of reduced width towards the lower end of the plate, a lower plate having an elastic connection with said upper plate beyond the larger end of said stud receiving opening, a rigid stud carried by said lower plate, and a resilient boss extending from the face of 15 said lower plate adapted in the operative position of the device to lie within the stud receiving opening in the upper plate and engaging the top wall thereof.

2. A clasp for a garment supporter as defined 20 in claim 1, in which said resilient boss at its one end closely overlies the upper side of said stud and extends upwardly therefrom a sufficient distance whereby to provide with said stud a longitudinal filler for said stud receiving opening. 25

JOHN ROBIE PARKER.
